2,313,851

METHOD FOR OPERATING PHONOGRAHS

Harry R. Van Deventer, New York, N. Y., assignor
to Peatrophone Corporation, New York, N. Y.,
a corporation of Nevada

Application January 25, 1941, Serial No. 375,884

7 Claims. (Cl. 274—46)

This invention relates to improvements in method of and apparatus for operating phonographs and processing records therefor, and has for its object the provision of a phonograph instrument using a re-usable record blank—that is to say, a sound record may be recorded on the blank, played back, the recording obliterated from the blank without removing any material therefrom, and another recording made thereon—and this process repeated indefinitely.

Another object is to provide a device of the character described in which the record blank remains in situ in the machine, and may be repeatedly used without shaving the blank.

Another object is to provide a method of processing a record blank for phonographs including the steps of recording on said blank, obliterating said recording, and preparing said blank for use again by heating the same while it remains in situ.

Other objects are the provision of a method of processing record blanks by obliterating the recording surface by heat wherein the length of time the blank is heated by apparatus associated with the phonograph, or the temperature to which the blank is heated, is pre-determined by such apparatus, or where the application of heat to the blank is controlled by the density thereof.

Other objects will be apparent from a perusal of the following specification and claims, where, by way of illustration, one embodiment of the apparatus necessary to carry out the method herein disclosed and claimed is described and illustrated. It will be understood, however, that the construction of the apparatus may be varied in wide limits from that shown and described, without departing from the inventive concept as defined in the appended claims.

In the accompanying drawings—

Figure 1 is a side view, partly in section, of apparatus for carrying out the method of processing phonograph records herein described;

Figure 2 is a wiring diagram of the circuits of the apparatus shown in Figure 1;

Figure 3 is a detailed view of apparatus used when the application of heat to the record blank is controlled by the density thereof;

Figure 4 is a diagram of an alternate method of connecting up the controls necessary in carrying out the herein described method; and

Figure 5 is a plan view of the underside of the heater unit 16 of Figure 1.

In phonographs where the character of the record is such that it is not desired to keep the

record—for instance, in telephone message recorders, such as that shown in co-pending application Serial No. 333,268, filed May 4, 1940, U. S. Patent No. 2,261,420, dated November 4, 5 1941, where the recorded message is played back once or twice and the record then thrown away, and with ordinary dictating machines—it is desirable to have a record blank that needs no renewal and that can be treated without removing 10 the same from the machine to wipe out any sounds recorded thereon and prepare the surface of the blank for further recording.

In phonographs employing disc record blanks, it is necessary to change the blank when full, 15 as no satisfactory means exist to remove the recording and use the blank. This is particularly true of record blanks for so-called home recorders which are commonly made of cardboard discs coated with suitable material on which the 20 recording is made.

With machines using cylinder blanks, such as the well-known Edison phonograph, it is possible to shave off the recording and use the blank repeatedly, but the blank is gradually worn away, 25 and must ultimately be replaced. As the blank is shaved, it gradually disappears and the cuttings are thrown away. As a sound record is recorded, the cuttings are also thrown away, and in both cases no effort is made to return 30 these cuttings to the individual record from whence they came.

The herein disclosed method and apparatus eliminates the above difficulties and provides a record which may be termed "perpetual" in that 35 it may be used over and over again while remaining in situ. By "in situ" as hereinafter used in this specification and the claims, is meant that the record remains in place associated with the recording and reproducing mechanism of the 40 phonograph while it is treated in accordance with the method herein disclosed.

While for the sake of illustration the record blanks herein shown are of the flat or disc type, it will be understood that by the use of suitable 45 apparatus, cylinder blanks can be used, or the record blank may be of any form such as a tape, and while the accompanying specification discloses a phonograph in which the record is moved, it will be obvious that this method may be applied to phonographs in which the record remains stationary while the recording and reproducing mechanism moves over it.

In Figure 1, the numeral 10 denotes the usual 55 revolvable record table of a phonograph such as commonly employs disc record blanks. This table,

instead of merely supporting the usual blank, is made in the form of a shallow pan having an upstanding flange 11. This pan is filled with any suitable material 12 upon which recordings can be made.

There are many suitable materials, usually special wax compositions well known in the art, as well as metallic and plastic compounds. To practice this method the material may be anything suitable that will soften sufficiently when heated so that a recording made on the surface of the material may be obliterated by heating the upper surface of the blank until it is smooth, and then cooling the same to a proper condition for further recording thereon. For the sake of brevity this record material will hereinafter be referred to as a "wax," a term commonly used to describe wax-like compounds used for this purpose.

If the record table is provided with a separable joint 13, whereby it is connected to the driving shaft 14 of the usual driving motor 15, it could be lifted off the drive shaft and heated in any suitable manner, cooled and returned to the phonograph. But this procedure would be objectionable in many cases; for example, in offices and the like where no facilities exist for heating the record table and properly handling it, excluding dust, etc., and maintaining the surface level while the wax is in liquid form, such procedure would be difficult and would prevent this method from being used, where the records would be handled by laymen.

This method of lifting the record table off the drive shaft and heating it may be used in studios and other places where the work is done by experts, and this disclosure, to-wit, that of providing a removable table holding a compound that can be melted and used over and over, is therefore useful although it is not the preferred embodiment of the broad idea.

The heating of the record can be done without removing the record table from the phonograph, and advertizing to Figure 1, which shows the record table in the usual position it occupies in a phonograph, an electric heater 16 is mounted so that it may be swung down and over the recording surface of the wax 12, the usual recording or reproducer arm (not shown) being moved out of the way to permit this.

The heater 16 may be of any suitable type, preferably a hot plate having a smooth heating surface adjacent the wax. If desired, an exposed coil type of heater may be used wherein the heating coil 17 is directly exposed to the surface of the wax. As there are many types of suitable heaters, no attempt will be made to describe one in detail, such heaters being in common use in connection with waffle irons, smoothing irons, and many other appliances.

The heater unit 16 is mounted on a suitable support 18 by means of a spring hinge 19, the spring 20 being disposed in relation to the parts of the hinge in a well known manner to cause the heating unit to normally assume the open position shown in the dotted lines 21—that is to say, spaced apart from the wax 12.

If necessary the heating unit may be mounted in the usual lid commonly employed with phonographs, or it may be mounted under this lid, sufficient space being allowed to permit the heater to spring upward when released, as hereinafter described.

The purpose of having the heater unit hinged so that it can be moved upwards away from the 75

wax is that this materially shortens the cooling period hereinafter referred to.

While the circuit to the heater coil 17 can be controlled by manual switching mechanism, it is not desirable to do so because the operator may turn on the current, leave the phonograph and forget to turn off the current. Therefore, the circuit and apparatus shown in Figure 2 is provided, which not only automatically turns on the heating current but also properly times the application of the heat to the wax. This is hereinafter termed the "heating period," and this apparatus may also determine the "cooling period" hereinafter referred to.

15 When it is desired to process a record, assuming a recording has been made which it is desired to obliterate, the heater unit 16 is moved via the handle 18* (which may be of heat insulating material) to the position shown in solid lines in Figure 1 against the tension of the spring in hinge 19. This operates the plunger 22, pushing the same downward against the tension of and closing the switch springs carrying contacts 23, 24. This completes a circuit from the current supply 25—26, through the winding 27 of a thermostat 28, the contact 29 of which is normally closed, and through the winding 30 of a locking magnet, the pole piece 31 of which is in contact with the armature plate 32 attached to the heater unit. As the armature plate is magnetically held against the pole piece of the magnet by reason of the current flowing in the coil 30, the heater unit 16 is thereby held in "heating period" position, during which period current also flows from current supply 25—26 via contacts 23, 24, the thermostat arm 28 and contact 29, and through the heating coil 17, thereby heating the heater 16 which in turn heats the adjacent wax 12.

40 The current continues to flow as just described until the heating of the winding 27 of the thermostat causes the arm 28 thereof to move and separate from the contact 29. This opens the circuit through the coil 30, and the core 31 is de-magnetized, releasing the armature plate 32 secured to the heater unit 16 which is released and immediately moves (under the influence of the spring hinge 19) to the upper position shown in dotted lines 21 in Figure 1. At the same time it will be noted the circuit is opened through the heating coil 17, so that immediately the heating unit 16 begins to cool.

Obviously, the length of time required for the thermostat arm 28 to move to open the circuit as just described, can be predetermined by the adjustment of contact 29, and the "heating period" can, therefore, be regulated by adjusting the thermostat, or by any other means such for example as by introducing a variable resistance into the heater circuit.

60 Referring to Figure 1, it will be observed that there is a contact 33 which can only contact with the spring arm 23 of the switch mechanism controlled by the position of the heater unit, when the heater unit is in non-operating (upper) position, and that this contact 33 controls the operating circuit to the motor 34 in which circuit a manual switch 35 may be inserted if desired. Obviously, as long as the heater unit is in "heating" position, the motor circuit will be open at contact 33, regardless of whether the switch 35 is open or closed and the motor cannot be operated; therefore the turn table 10 cannot be rotated and the wax 12 disturbed by rotation while the record is being processed. But as

soon as the "heating period" is terminated and the winding 30 releases the heater unit 16, the circuit is established through the contact 33 and then the motor 34 may be operated by closing the switch 35.

While the thermostat or thermal relay 28 may be so timed or adjusted that it will not open its contacts until the wax 12 is melted sufficiently to obliterate the recording thereon, and at this point the control circuit is opened, thereby releasing the heater unit 16 and disconnecting the heating coil 17, if this heater unit (which will remain hot for a time if once heated) remained close to the wax, the residual heat in it would keep the wax soft over a longer period of time than desirable, and to shorten this "cooling period" so that the phonograph can be used without undue delay, the heater unit is automatically raised from the wax as previously described. As the pan or table 10 holding the wax can be made of thin material, or some nonmetallic material, it will not store much heat, so that moving the heater unit away from the wax enables the latter to cool with comparative rapidity.

It will be understood that it is unnecessary to heat the entire body of wax. The application of sufficient heat to just melt the upper surface is sufficient—a slight application of heat will cause the wax to "blush," whereupon the recordings will disappear, as they are very shallow.

Occasionally the entire mass of wax can be melted in order to insure uniformity, and at such time the cuttings which are normally made during recording can be placed on top of the wax 12 and melted therein so that but little wax will be lost over a long period of time. This thorough heating can be accomplished by adjusting the thermostat 28.

The "cooling period" can also be predetermined by adjustment of the "make" period of the thermostat, or in any other manner.

With some materials, it may be desirable to control the application of heat to the record blank directly by the density thereof, instead of relying on the timing of thermostat 28. To accomplish this, the apparatus now to be described may be placed in circuit with the thermostat.

Referring to Figure 3, the numeral 36 generally denotes a device that may be mounted upon the heater unit 16 preferably at the center thereof, as no recordings are made at the center. This blank space in the record material can be utilized by placing in the center of the unit 16 a bearing block 37 in which is slidably mounted the plunger 38, the bottom end of which is given any suitable formation to properly engage the upper surface 12 of the wax when the heater unit is in heating position.

Obviously, as long as the wax is hard, the contact members connected to the wires 39 and 40 will be held in engagement by the upward push of the stem of plunger 38 as it is held up by the wax 12 and the circuits through the winding 30 of the holding magnet and the heater coil 17 are closed. However, when the wax 12 melts, the plunger 38 will move downwardly therein, under the action of the spring contact member in contact therewith, thereby permitting the contact members connected to 39 and 40 to open the circuit through the winding 30 and the heater coil 17. It will be observed that this opening is dependent upon the density of the wax 12 and cannot take place until the wax is soft enough to receive the plunger.

At the end of the operation just described, the 75

plunger 38 would be imbedded in the wax, as shown by the dotted line 41 in Figure 3, but a quick upward jerk of the handle 16^a of the heater unit on which the plunger contact mechanism is carried will dislodge the plunger, leaving a small hole in the center of the wax disc. As this center is not traversed by either the recorder or the reproducer, the presence of this hole is not objectionable.

10 A study of Figure 2 will reveal that as soon as the thermostat 28 is operated, (or if the device 36 is used as soon as it operates), while magnet coil 30 is deenergized and the heater unit 16 released so it can move to non-operating position, that the motor circuit is completed at contact 33 and it is therefore possible to start the motor. This is objectionable, because the wax 12 may be too soft to take a recording. While a "cooling period" can be determined by adjusting the thermostat 28 as previously mentioned, the following means is preferred to insure that a suitable "cooling period" elapses before the motor can be started.

25 Referring to Figure 4, the apparatus enclosed in the dotted line 42 represents diagrammatically any suitable type of cyclic timing mechanism, such as an ordinary electric or spring-driven clock or timing device having a suitable switching mechanism such as that diagrammatically indicated at 43. When it is desired to start the heating apparatus, the movable member 43 of the switching mechanism is placed on the insulatedly mounted contact segment 44 and the clock is started. As long as 43 and 44 are in contact, the circuit will be closed and current will flow through the winding 30 and the heating coil 17, thus determining the heating period, while the motor circuit will be open, as shown.

30 35 40 45 50 When the member 43 rides off the segment 44 onto the insulatedly mounted segment 45, the circuit through 30 and 17 is opened, and the motor circuit also remains open. The length of this "cooling period" depends upon the length of segment 45, and can therefore be predetermined. As the circuit is open through the motor 34, it is impossible to start the latter until the member 43 makes contact with the insulatedly mounted segment 46 whereon the timing device comes to rest, and while at rest the circuit is completed through the motor 34, as shown.

55 60 65 It will be observed from a study of the foregoing figure that the arrangement described provides, first a "heating period," immediately followed by a "cooling period," and during both of these periods it is impossible to start the motor of the phonograph.

By introducing the mechanism shown in Figure 3 into the circuit Figure 4, as shown, it is of course possible to control the "heating period" by the density of the wax 12, as previously described. It will also be understood that if the timing arrangement shown in Figure 4 is used, it is not necessary to employ the switch mechanism shown in Figure 1 as controlled by the plunger 22; although if for any reason it is desired to use contacts 23, 24, thereof, they may be serially included in the circuit as shown at 47, in Figure 4.

70 75 When, as previously stated, the record table or container 10 for the wax is removed from the phonograph instrument of which it is a part, and the sound recording on the meltable material or wax 12 is obliterated by means of heat, this heat can be applied in any suitable manner.

However, it is desirable to apply it by means of the apparatus herein described, insofar as timing the application of it is concerned to prevent overheating and perhaps burning the wax. Obviously, when the container is removed from the phonograph to perform this operation, no necessity arises to disable the motor circuit of the phonograph to provide a "cooling period" as previously described, and this feature can be eliminated when the container is heated outside; obviously it would not be replaced in the phonograph until the wax 12 is cool enough to record thereon.

It will be obvious from the preceding description that the type of record is immaterial, provided it has a meltable surface on which sound recordings can be made by any suitable type of recorder—either by mechanical cutting or embossing or by any other means. An appropriate reproducer of any suitable type may also be used with these records in the ordinary manner.

Also it will be apparent that the heater 17 can be combined with the container 10 so as to form part thereof. In this event, a longer "cooling period" will be necessary because the heater coil 17 and the surrounding material must cool as well as the wax 12 in contact therewith, so that the drawings show a preferred form of the invention, as with the movable heater as shown the "cooling period" is considerably shortened, as compared with any of the obvious modifications wherein the heater is combined and always remains in heat exchange relation with the record or its support.

The separable joint 13 can be of any suitable construction that permits the removal of the container in rotatable relationship to the driving shaft of the motor. The attachment of the joint 13 to the bottom of the container is preferably liquid-tight so that all the wax can be liquefied therein without finding egress at this point. The motor 15, heater 16 and its support 19, 20, the coil 30 and the contact mechanism 23, 24, 33, and, if desired, the thermostat 28, 29, can all be mounted upon a common base 48 in any suitable manner.

Obviously each phonograph can be provided with spare containers so that when one of them is in use on the machine, the records on others can be processed as herein described either in situ or by removing the containers.

What is claimed is:

1. A method of processing record blanks for phonographs which consists of confining a body of meltable material in a container forming part of a phonograph instrument, recording sound upon said material while the material is at substantially the temperature of its surroundings, and in a solid state, and obliterating said recording by the application of heat to the entire recording surface of said material while the body of same remains in a solid state and while same is confined in said container and at rest in position in the phonograph instrument.
2. A method of processing record blanks of solid material for phonographs including the first step of forming a surface adapted to receive a recording on the blank by heating said surface while the remainder of said blank remains solid, while said record is at rest, the second step of cooling the surface of said blank to approximately the temperature of its body portion and surroundings, and the third step of recording on said surface, all said steps being performed while the blank is in situ.
3. The method of treating records for eradicating recordings from the surfaces thereof which includes the step of positioning a source of radiant heat adjacent to and overlying said record to reduce the entire surface of said record to a smooth state, removing said source, and permitting said surface to cool and set.
4. The method as claimed in claim 3 including the further step of automatically predetermining the length of time said radiant heat source is applied to said record.
5. The method as claimed in claim 3 including the further step of automatically predetermining the maximum temperature to which said record is heated.
6. The method as claimed in claim 3 including the further step of controlling the application of heat to the record by changes in the density thereof.
7. The method of treating disc records for eradicating recordings from the surfaces thereof which includes the steps of supporting said record substantially level, positioning a source of radiant heat adjacent to and overlying said record to reduce the entire surface of said record to a smooth state, removing said source, and permitting said surface to cool and set.

HARRY R. VAN DEVENTER.
